(57) **CLAIM**

The ornamental design for an electric neck warmer, as shown and described.

DESCRIPTION

FIG. 1 is a top plan view of an electric neck warmer showing my new design;

FIG. 2 is a bottom plan view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top, front and left side elevational view thereof; and,

FIG. 8 is a top, front and right side elevational view thereof. The broken lines in the drawings illustrate the portions of the electric neck warmer which form no part of the claimed design.
